US00D875527S

(12) **United States Design Patent** (10) Patent No.: **US D875,527 S**
(45) Date of Patent: **** Feb. 18, 2020**

(54) **CLOSURE WITH GRIP FEATURES**

(71) Applicant: **Henkel IP & Holding GmbH**,
Duesseldorf (DE)

(72) Inventors: **Daniel Peter Sterling**, Fairfield, CT
(US); **Elizabeth Meriwether Boyd**,
Auburn, AL (US); **Glenn William
Kaye**, Stamford, CT (US); **Anne
Elizabeth Lindert Nixon**, Newtown,
CT (US)

(73) Assignee: **Henkel IP & Holding GmbH** (DE)

(**) Term: **15 Years**

(21) Appl. No.: **29/621,456**

(22) Filed: **Oct. 9, 2017**

(51) LOC (12) Cl. **09-07**
(52) U.S. Cl.
USPC **D9/453; D9/443**

(57) **CLAIM**

The ornamental design for a closure with grip features, as
shown and described.

DESCRIPTION

FIG. 1 is a top perspective view taken from one embodiment
of our new design for a closure with grip features;

FIG. 2 is a top view thereof;

FIG. 3 is a bottom view thereof;

FIG. 4 is a front view thereof;

FIG. 5 is a right side view thereof;

FIG. 6 is a left side view thereof; and,

FIG. 7 is a rear view thereof;

FIG. 8 is a top perspective view taken from a second
embodiment of our new design for a closure with grip
features;

FIG. 9 is a top view thereof;

FIG. 10 is a bottom view thereof;

FIG. 11 is a front view thereof;

FIG. 12 is a right side view thereof;

FIG. 13 is a left side view thereof; and,

FIG. 14 is a rear view thereof;

FIG. 15 is a top perspective view taken from a third
embodiment of our new design for a closure with grip
features;

FIG. 16 is a top view thereof;

FIG. 17 is a bottom view thereof;

FIG. 18 is a front view thereof;

FIG. 19 is a right side view thereof;

FIG. 20 is a left side view thereof; and,

FIG. 21 is a rear view thereof;

FIG. 22 is a top perspective view taken from a fourth
embodiment of our new design for a closure with grip
feature;

FIG. 23 is a top view thereof;

FIG. 24 is a bottom view thereof;

FIG. 25 is a front view thereof;

FIG. 26 is a right side view thereof;

FIG. 27 is a left side view thereof; and,

FIG. 28 is a rear view thereof.
